UNITED STATES PATENT OFFICE.

ARCHIBALD S. WATSON, OF DETROIT, MICHIGAN, ASSIGNOR TO DETROIT HOIST AND MACHINE COMPANY, OF DETROIT, MICHIGAN, A CORPORATION OF MICHIGAN.

ELECTRIC HOIST.

1,238,466.

Specification of Letters Patent. Patented Aug. 28, 1917.

Application filed October 22, 1912. Serial No. 727,11

To all whom it may concern:

Be it known that I, ARCHIBALD S. WATSON, a citizen of the United States of America, residing at Detroit, in the county of Wayne and State of Michigan, have invented certain new and useful Improvements in Electric Hoists, of which the following is a specification, reference being had therein to the accompanying drawings.

10 My invention relates to hoists and resides in the novel construction of a magnetic brake; in the peculiar arrangement and construction of the mechanical clutch and brake, and in certain details of construction, as will 15 more fully hereinafter appear.

In the drawings,—

Figure 1 is a front elevation of the device embodying my invention, partly in section;

20 Fig. 2 is an end elevation of a portion of a frame; and

Figs. 3 and 4 illustrate certain details of arrangement.

1 designates the frame of the hoist and 2 the motor mounted thereon. 3 is a driving shaft forming an extension of the motor shaft and 4 designates the shaft of the winding drum 5 in the form of a hollow member sleeved upon the shaft 3 and suitably journaled in bearings 6 and 7 in the frame. The 25 shaft 3 has the outer end thereof journaled in a bearing 8 and is free to rotate, independent of the sleeve 4. The outer end of the member 3 projects beyond the bearing 8 and is fixedly secured to one of the coöperating members as 9 of a cone clutch. The 30 other coöperating member 10 is secured to the casing against rotation as by means of lugs 11, but is free to slide longitudinally. 35 12 is a magnet controlling movement of the member 10 in the usual manner.

In order that the magnet may be readily accessible for repair, I arrange the magnet casing 13 exteriorly of the end 14 of the frame, and preferably the end 14 is provided with a recessed portion within which the armature casing is detachably secured as by means of screws 15. The armature 16 of the magnet also is arranged exteriorly of the casing end and within the recessed portion, the armature being attached to the brake member 10 by means of a shaft or stud 17 which is slidably mounted in a bearing 18. As is usual in this type of brake the armature is normally held away from the magnet by means of a spring as 19, which tends

to retain the coöperating portions of the brake in the desired frictional engagement.

It frequently becomes necessary to adjust the tension of the spring so as to take up wear between the cone members, or to readjust the latter to different kinds of work. I have, therefore, positioned the spring 19 in a central bore 20 in the magnet and provided an adjustable abutment for the outer end of the spring in the form of a screw 21 having a threaded engagement with the bore 20 and accessible through the outer end of the bore, which is open. The other end of the spring 19 engages a pin 22 that has a sliding engagement with the inner end of the magnet bore. This pin has a bearing on the inner face of the armature but is not attached to the latter, since by forming the pin free from the armature it is not necessary to accurately align the bore 20 with the bearing 18 of the shaft 17. It will be readily appreciated that if the magnet were arranged within the frame, and the pin 22 was fixed to the armature a very accurate alining of the bearings 17 and bore 20 would be required, in order to avoid binding of the parts.

The drum 5 is driven from the shaft 3 through a step-down drive train. As shown, 23 is a counter-shaft journaled in suitable 35 bearings 24 24^a, in the frame or casing 1, and 25 is a sleeve surrounding the counter-shaft and free to rotate in relation thereto. This sleeve is driven from the shaft 3 by means of a gear 26 and pinion 27 fixed respectively to the sleeve and the shaft. The counter-shaft is rotated from the sleeve 25 through the medium of a combined clutch and brake mechanism to be hereinafter described. Fixedly secured to the counter-shaft is a pinion 28 meshing with a gear 29 upon a tubular extension 30 that is loose on the hollow shaft 4, this extension being preferably integral with a pinion 31 engaging a gear 32. The latter member is fixedly secured to a pinion 33 that drives a gear 34 attached to the shaft 4 of the drum. Both the gear 32 and pinion 33 are loosely mounted on a stud shaft 23^a arranged in a bearing 23^b in the casing. This stud shaft is preferably in alinement with the shaft 23 but is independent thereof and stationary so as to avoid the wear and friction that would necessarily occur if the member 23^a was an extension of the shaft 23. Thus, upon rota-

110

tion of the shaft 3 the pinion 27 drives the gear 26, which rotates the sleeve 25, driving through the medium of the combined clutch and brake mechanism the shaft 23. Upon 5 rotation of the latter the member 28 rotates the drum shaft 4 through the intermediate gears 29, 31, 32 and 33 and the gear 34.

The combined clutch and brake connection between the sleeve 25 and shaft 23 is preferably of the friction disk type and comprises coöperating members or heads 35 and 36 both splined to the shaft 23, and intermediate friction disks 37 and 38. The disks 37 also are splined to the shaft 23 and the 15 disks 38 are provided with peripheral bearings 39 engaging pins 40 projecting laterally from a member 41 which has a hub 42 loosely mounted upon the hub 43 of the head 36. Surrounding the hub 42 is a brake member 44 which has cam recesses 45 within 20 which are arranged rollers 46. The brake member is held against rotation preferably by providing the same with flat peripheral portions 56 for engaging similar surfaces 57 on the casing. Upon rotation in one direction the hub 42 is free to revolve in relation to the brake mechanism, but upon rotation in the opposite direction the rollers 46 will be forced by the cam recesses into 25 frictional contact with the hub 42 and lock the latter against movement.

Upon forward rotation of the shaft 3 the frictional disks are clamped together by means of coöperating cam faces 47 and 48 35 on the adjacent ends of the sleeve 25 and the head 35. These cam faces comprise oppositely arranged spiral inclines forming shoulders 49 and 50 which in the released position abut or are in immediate proximity 40 to each other. However, when the sleeve 25 is driven in the direction to hoist the cam 47 is moved relative to the cam 48 in a direction to cause the cam faces to separate the sleeve 25 and the head 35, thereby forcing 45 the latter inward and clamping the frictional disks.

In operation, assuming that the motor is to be driven in the forward direction, or in the direction to hoist, upon turning on the 50 current the magnet 12 will be polarized, attracting the armature and withdrawing the brake member. The releasing of the brake will permit the shaft 3 to be rotated in the direction indicated by the arrow *a*, which 55 will drive the sleeve 25 in the opposite direction and cause a relative movement of the incline faces in a direction to force the head 35 inward and clamp the disks. This relative movement of the cam faces is effected since the load tends to resist rotation 60 of the shaft 23. Therefore, the greater the load the greater the clamping action upon the disks. In other words, the clamping of the clutch parts is proportional to the load.

65 The clamping of the disks rotatively se-

cures the member 41 to the heads 35 and 36 and as the roller brake permits free rotation of the hub 43 during hoisting, the friction disks and the heads form a clutch for coupling the sleeve 25 to the shaft 23.

During lowering of the load the friction device acts as a brake and the braking action also is proportional to the load. Thus, when the load is to be lowered the motor is reversed, driving the shaft 3 in the direction 70 opposite from that indicated by the arrow *a* and likewise reversing the remaining parts of the drive mechanism. The sleeve 25 then rotates as indicated by the arrow *b* which tends to move the incline faces 47 and 48 to 75 their normal position, or in the position to release the friction disks. The load however, tends to cause the shaft 23 to run ahead of the sleeve 25 so to speak, and the heavier the load the greater will be this tendency. Since 80 the member 35 is splined to the shaft 23 the action of the load will be transmitted thereto, resulting in the incline 48 being moved relative to the incline 47 and in a direction to force the head 35 inward. However, rotation of the member 41 in the reverse direction, as indicated by the arrow *c*, is prevented by reason of the roller brake 85 acting upon the hub 42. The disks 38, therefore, during lowering of the load are held 90 stationary while the disks 37 rotate, producing 95 a braking action that is dependent upon the pressure applied to the head 35, which pressure, as before stated, is proportional to the load. In case there is no load applied to 100 the hoisting hook during lowering, the cam 48 would be turned until the shoulders 49 and 50 abut, which would positively rotate the shaft 23 through the splined connection between the latter and the member 35.

105 The combined clutch and brake serves an additional function, namely,—to prevent the load running away in case the cone brake did not operate properly. Thus, if upon turning off of the current the friction engagement of the parts 9 and 10 was not sufficient to stop the mechanism, any tendency of the load to run ahead of the sleeve 25 would result in the forcing of the member 35 inward, which as before described, would 110 cause the friction disks to act as a brake.

In order to condense the structure and at the same time provide necessary bearings for the several shafts and sleeves, the frame or casing 1 is divided by an integral vertical partition 51 into complementary chambers 52 and 53. Within the former chamber the step-down drive train is arranged, while within the latter are positioned the combined clutch and brake and the magnetically 115 operated cone brake. The bearing 8 for the shaft 3, and the journal 24^a for the sleeve 25 are formed in the vertical partition 51, while the journal 24 for the shaft 23 is in a head 54 that closes a hollow cylindrical 120 125 130

projection 55 forming a housing for the roller clutch. Ready access to the clutch parts is had by forming the head 54 detachable.

- 5 What I claim as my invention is:—
In an electric hoist, the combination with a drive and driven member, of a driving connection between said members including coöperating relatively movable clutch
10 heads secured to one of said members, said heads having hubs, coöperating friction disks interposed between said heads, a portion of which are attached to the last-mentioned member, a member loosely mounted
15 on one of said hubs and provided with a laterally projecting pin to which the remain-

ing portion of the disks are connected, a connection between the casing and the last mentioned member permitting movement of the latter in one direction and withholding 20 the same against rotation in the opposite direction, the other of said hubs and the other of said drive and driven members being provided with engaging oppositely disposed inclined bearing faces. 25

In testimony whereof I affix my signature in presence of two witnesses.
